UNITED STATES PATENT OFFICE.

FRANK J. STEPHENSON, OF ROYERSFORD, PENNSYLVANIA.

FLASK-CHARGING APPARATUS.

Application filed June 28, 1921. Serial No. 481,023.

To all whom it may concern:

Be it known that I, FRANK J. STEPHENSON, citizen of the United States, residing at Royersford, in the county of Montgomery and State of Pennsylvania, have invented certain new and useful Improvements in Flask-Charging Apparatus, of which the following is a specification, reference being had therein to the accompanying drawing.

The present invention relates to apparatus for charging molding flasks with sand or mold-material under pressure, and aims to provide a novel and improved apparatus of that character which is comparatively simple in construction and operation, as well as practical and efficient in use.

Another object is the provision of novel means for projecting the sand or material at a high velocity into the flask, in order to pack the sand in the flask, and to provide for the convenient and rapid filling and packing of the flask with the material.

A further object is the provision of a jointed or flexible arm supporting the sand projecting means, for the movement of said means to different positions, and of such construction as to supply the projecting means with sand through the arm.

A still further object is the provision of novel means for bracing the arm against depression under the weight imposed thereon.

The invention also has for its object the improvement of the construction in its details and arrangement of parts, to enhance the utility and efficiency of the apparatus.

With the foregoing and other objects in view, which will be understood as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a vertical section of the apparatus taken substantially on the line 1—1 of Fig. 2, portions being shown in elevation.

Fig. 2 is a front view of the apparatus.

Fig. 3 is a fragmentary vertical section 55 of a modified form of apparatus.

In the embodiment of the machine as shown, a platform 7 is supported from upwardly-converging posts or supports 8, and a hopper or bin 9 for the sand or mold material is mounted on said platform, and is supplied with sand from an elevator 10. The hopper 9 has a trough 11 at the bottom thereof with a discharge spout 12 depending through the platform 7. A conveyor worm or helix 13 works within the trough 11 and is carried by a shaft 14 extending longitudinally within the trough, for feeding the sand to the discharge spout 12 from which it drops by gravity. As shown, the shaft 14 is connected at one end to an electric motor 15 mounted on the platform 7, to operate the worm 13.

A jointed arm is connected to the spout 12 of the hopper, and includes an inner horizontal tubular section 16 provided at its inner end with an upturned receiving neck 17 swivelled for turning movement in the spout 12, in order that the section 16 can be swung about a vertical axis. The swivel connection, as shown, includes an annular outstanding flange 18 in the neck 17 disposed within the spout 12 and seated on anti-frictional balls 19 which travel on an annular ball race and retaining collar or ring 20 engaged within the lower end of the spout 12. The arm section 16 is thus suspended for swinging movement in a horizontal plane, and a packing ring 21 is preferably disposed between the flange 18 and shoulder of the spout 12, to prevent leakage of sand out between the spout 12 and neck 17. The section 16 has a depending discharge spout 22 at its outer end.

In order to feed or move the sand outwardly in the section 16 from the receiving neck 17 thereof to the discharge spout 22, a conveyor worm or helix 23 is disposed in said section, and is mounted on a longitudinal shaft 24 journaled through the opposite ends of said section. As shown, one end of the shaft 24 is connected to an electric motor 25, for driving said worm 23, and the motor is mounted on a shelf 26 supported from the section 16.

The jointed arm includes an outer tubular horizontal section 27 provided at one end with an upstanding or upturned receiving neck 28 which is swivelled for turning movement in the spout 22 in the same manner that the neck 17 is swivelled.

in the spout 12. Thus, the neck 28 has a flange 29 seated on anti-frictional balls 30 which travel on collar or ring 31 secured within the spout 22, and a packing ring 21' 5 is disposed between the flange 29 and shoulder of the spout 22. In this manner, the section 16 of the arm can not only be swung about the vertical axis of the hopper spout 12, but the section 27 can be swung 10 in a horizontal plane around the vertical axis of the spout 22, to move the free end portion of the arm to different positions within the reach of said arm. The section 27 has a depending discharge spout or 15 lower outlet 32 at its free end, and the material is fed or moved outwardly in the section 27 by means of a conveyor worm or helix 33 carried by a longitudinal shaft 34 journaled through the opposite ends of the 20 section 27. The worm 33 feeds the sand from the receiving end of the section 27 to the discharge spout or opening 32.

The sand projecting means includes a rotary spout 35 below the spout or outlet 32 25 of the jointed arm, and, as shown, the spout or shell 35 is tapered downwardly whereby the stream of sand is concentrated, to reduce the spreading of the sand to a minimum. The spout 35 is provided therein with a projecting helix 36, which can have one or more blades according to the requirements, said helix and spout being fastened together or integral, and the helix being secured on a vertical shaft 37 which is journaled through 30 the top of the section 27 above the spout or outlet 32. The upper end of the spout 35 can be offset or flanged, as at 38, to surround the spout 32.

The driving means for the projecting 40 helix 36, as shown, includes an electric motor 39 above the section 27 of the arm to which the upper end of the shaft 37 is connected, thus providing a direct drive for the helix 36. Furthermore, the outer end of the shaft 45 34 can also be connected with the motor by suitable gears 40 or other operative connection.

As a means for supporting the jointed arm against sagging under the weight of 50 the arm, sand, and parts carried by the arm, a jointed bracing device is employed. Such device includes a post 41 secured to and rising from the section 16 of the arm near the outer end thereof and coaxial with the 55 spout 22 and neck 28, and an inclined brace 42 has its lower end portion engaging the post 41 near the upper end of said post, and the upper end portion of the brace 42 is engaged over a pivot stud 43 rising from a 60 cap piece 44 secured on the upper ends of the posts 8. Suitable retaining means 45 is engaged on the stud 43 to hold the brace 42 thereon. An outer inclined brace 46 has its upper end engaged over the upper end 65 of the post 41, and a nut 47 or other means

is also engaged on the upper end of said post over the braces 46 and 42, while the lower end of the brace 46 is secured, as at 48, to the arm section 27. The post 41 is thus supported by the brace 42, which 70 in turn supports the section 16 of the arm, while the brace 46 is supported from the post 41 and brace 42, thereby supporting the arm section 27, and said braces 42 and 46 can turn or swing with the arm sections 75 16 and 27, respectively. The brace 46, as shown, has a portion 49 to which the motor 39 is secured, and brackets 50 can also be secured to the opposite sides of the section 27 and motor 39 to assist in holding said 80 motor in place. It is preferable to provide anti-frictional balls 51 between the adjacent ends of the braces 42 and 46 and also between the brace 42 and cap piece 44, to permit the braces to turn freely, as well as 85 the sections of the arm.

Although the conveyor worms 13, 23 and 33 are independently motor-driven, they can be operated by other means, as will be apparent, for conveying the sand to the 90 spouts 12, 22, and 32 in succession from the hopper or bin through the arm.

In using the apparatus for charging a flask 52 with sand or other mold-material, the flask is brought to a position, either on a 95 truck or otherwise, where the projecting means can be brought above the flask, it being noted that the jointed arm permits such means to be moved about with considerable latitude. The worms 13, 23 and 100 33 will convey the sand to the spout 12, through the arm section 16 to the spout 22 and through the arm section 27 to the spout or outlet 32, in succession, thereby automatically supplying the sand or material 105 through the jointed arm which supports the projecting means. The projecting helix 36 and spout 35 being rotated at a high velocity, will project the sand downwardly with considerable force, so that the sand will be 110 packed in the flask 52 under the desired pressure. The spout or nozzle 35 will concentrate the sand in a stream, and as the sand drops from the spout or outlet 32 into the spout or nozzle 35, the action of the 115 helix 36 will impart a rapid accelerated velocity to the sand in its downward movement through the spout or nozzle 35. The tapered form of the spout 35 will counteract the centrifugal force, to avoid the spreading 120 of the stream of sand when leaving the spout or nozzle 35.

Fig. 3 shows some variations. In this form, the spout 35' is cylindrical and the helix 36' is of similar outline, and the motor 125 39' is mounted on the arm section 27 and is connected by bevel gears 40' with the upper end of the shaft 37, whereby to rotate the helix 36' at a high velocity greater than the speed of the motor.

The conveyor worm 33 is also driven from the motor 25 of the worm 23. Thus, a pulley wheel 54 is secured on the inner end of the shaft 34 and a belt 55 passes around 5 said pulley wheel and around idler pulleys 56 carried by the arm 27 below the pulley wheel 54. The belt 55 passes around a double pulley wheel 57 supported for rotation from the section 27 below the same and 10 in the axis of the joint between the sections 16 and 27. A belt 58 passes around the pulley 57 and past idler pulleys 59 supported by a hanger suspended from the shelf 26, and said belt passes over a pulley wheel 61 15 secured on the shaft 24. The pulley wheel 57 is thus driven from the motor 25 in any angular position of the arm section 27, and the power is transmitted by the belt 55 to the shaft 34. This provides a flexible operative 20 connection between the shafts 24 and 34, permitting the sections of the arms to swing relatively to one another without interfering with the transmission of power.

A sand-directing funnel or guide 62 is 25 suspended from a hanger or bracket 63 from the section 27 with its upper large end surrounding the spout 35' and its lower smaller end directed downwardly. One or more vertical or longitudinal baffle plates or partitions 64 can be provided in the funnel 62. The function of the funnel is to direct the sand downwardly in a stream without spreading objectionably. Thus, the funnel being tapered downwardly will not only 30 direct the sand down in a small stream from the spout, but, furthermore, the plate or baffle 64 will prevent the whirling or rotation of the sand when passing from the funnel, inasmuch as said baffle or partition 35 will stop the whirling motion of the sand 40 while passing through the funnel.

Having thus described the invention, what is claimed as new is:—

1. A flask charging apparatus having a 45 discharge portion with a helix rotatable at a high speed for projecting the sand to a distance from said portion at a high velocity, and a funnel through which the sand is projected for counteracting the tendency 50 for the sand to be scattered.

2. A flask charging apparatus having a discharge spout and a helix therein rotatable at a high speed for projecting the sand to a distance from the spout at a high velocity, and a funnel through which the sand is 55 projected from said spout for counteracting the tendency for the sand to be scattered and formed with means tending to prevent the whirling motion of the sand.

3. A flask charging apparatus having a 60 rotatable discharge spout and a helix therein for projecting the sand at a high velocity from the spout.

4. A flask charging apparatus having a 65 discharge portion, a vertical shaft with its

lower terminal at said discharge portion, means carried by the lower terminal of said shaft to be rotated at a high speed for projecting the sand downwardly to a distance from said discharge portion at a high velocity, and a funnel associated with said means through which the sand is projected for counteracting the tendency for the sand to be scattered. 70

5. A flask charging apparatus having a 75 discharge portion, a vertical shaft with its lower terminal at said discharge portion, a helix carried by the lower terminal of said shaft to be rotated at a high speed for projecting the sand downwardly to a distance 80 from said discharge portion at a high velocity, and a funnel associated with said helix through which the sand is projected by the helix for counteracting the tendency for the sand to be scattered. 85

6. A flask charging apparatus having a discharge portion, a vertical shaft with its lower terminal at said discharge portion, a helix carried by the lower terminal of said shaft for projecting the sand downwardly at 90 a high velocity, and a spout surrounding and carried by the helix. 95

7. A flask charging apparatus having means for supplying sand provided with an outlet, a spout extending from said outlet, 95 means within the spout for projecting the sand downwardly at a high velocity to a distance from the spout, and a funnel below said spout through which the sand is projected for counteracting the tendency for the 100 sand to be scattered.

8. A flask charging apparatus having means for supplying sand provided with an outlet, a spout depending from said outlet, a helix within the spout rotatable at a high 105 speed for projecting the sand downwardly at a high velocity to a distance from the spout, and a funnel below said spout through which the sand is projected for counteracting the tendency for the sand to be scattered and formed with means therein tending to prevent the whirling motion of the sand. 110

9. A flask charging apparatus having means for supplying sand provided with an 115 outlet, a rotatable spout depending from said outlet, and a helix within and rotatable with said spout for projecting the sand downwardly at a high velocity.

10. A flask charging apparatus including 120 a tubular arm extending substantially horizontally and having a lower sand outlet, a vertical shaft extending through said outlet, means above said arm for rotating said shaft, a helix carried by the shaft below said 125 outlet, and a spout surrounding and carried by the helix and cooperating therewith for directing the sand downwardly.

11. A flask charging apparatus including 130 an arm supported for swinging movement

1 and having tubular sections connected by a swivel joint through which the sections communicate with one another, sand projecting means carried by the free section of said arm 5 to be supplied with sand through said sections, and sand feeding means working within said tubular sections for feeding the sand in said sections from one section to the other to said projecting means.

10 12. A flask charging apparatus including a sand bin, an arm having tubular sections with a swivel joint through which the sections communicate with one another, one section of said arm having a swivel joint 15 with said bin for the swinging movement of the arm and to receive sand from said bin, sand projecting means carried by the other section of the arm, and sand feeding means working within said sections of the arm for 20 feeding the sand from the bin to said projecting means.

13. A flask charging apparatus including a jointed arm, sand projecting means supported by said arm for movement to different positions, and a jointed bracing means 25 for said arm having hingedly connected braces supported one from the other and

mounted to swing with and support said arm.

14. A flask charging apparatus including 30 a jointed arm having sections mounted for swinging movement, sand projecting means supported from said arms for movement to different positions, and a jointed bracing means for said arm including hingedly connected 35 braces supported one from the other and mounted to swing with and support the sections of the arm.

15. A flask charging apparatus including 40 an arm mounted for swinging movement in a substantially horizontal plane and having sections connected by a swivel joint, sand projecting means carried by the free section of said arm, a post carried by one section of the arm coaxial with said joint, a brace secured to the free section of said arm and engaging 45 said post, and another brace supported for swinging movement with the other section of the arm and also engaging said post.

50 In testimony whereof I hereunto affix my signature.

FRANK J. STEPHENSON.
